PAPER HOLDER

Filed Sept. 23, 1929

UNITED STATES PATENT OFFICE

HILARY G. KNOTH, OF DETROIT, MICHIGAN

PAPER HOLDER

Application filed September 23, 1929. Serial No. 394,508.

My invention relates to a new and useful improvement in a holding device and has for its object the provision of a device which may be mounted on a suitable support and adapted for suspending loose articles such as newspapers and the like against the support for retaining the same in position.

Another object of the invention is the provision of a holding device of this class which will lend itself to fabrication in sizes that it may accommodate a full sized newspaper in unfolded condition.

Another object of the invention is the provision of a device of this class which will be simple in structure, economical of manufacture, durable and highly efficient in use.

Other objects will appear hereinafter.

The invention consists in the combination and arrangement of parts hereinafter described and claimed.

The invention will be best understood by referring to the accompanying drawings, which form a part of this specification and in which

Fig. 1 is a perspective view of the invention,

Fig. 2 is a view taken on line 2—2 of Fig. 1,

Fig. 3 is a sectional view taken on line 3—3 of Fig. 2.

The invention comprises a supporting member having a main body 7, which may be attached by screws or the like to a suitable support 8. Each of the ends 9 and 10 of the main body 7 are bent outwardly and provided

with a notch adjacent the upper end of the outward edge. The engaging member formed from wire and formed preferably U shaped is rockably mounted on the outwardly projecting ends 9 and 10. The legs 12 and 13 of this U shaped member are angularly turned as at 14 to provide the portion 15 which engages the outer face of the angularly turned portions 9 and 10. The end 16 of the portion 15 is projected through an opening formed at the angularly turned ends 9 and 10 and serves as a pivot on which the rocking takes effect. Springs 17 connect the main body 7 with the legs 12 and 13 and serve to retain the U shaped engaging member in

such a position that the bight 18 will serve

to press an object positioned between the support 8 and the bight 18 firmly against the support 8 and serve to retain it in position. The bight 18 is provided with the outwardly offset gripping portion 19. Ribs 20 are pressed into the main body 7 and the ends 9 and 10 for reinforcing purposes, thus permitting the supporting member to be made from comparatively light material. The angularly turned ends 14 by engaging in the notches 11 serve to guide the engaging member in its movement into the engaging position and at the same time serve to prevent undue displacement of the end 16 from the opening formed at the angularly turned portions 9 and 10.

While I have illustrated and described the preferred form of structure, I do not wish to limit myself to the precise details of structure shown but desire to avail myself of such variations and modifications as come within the scope of the appended claims.

Having thus described my invention, what I claim is new and desire to have secured by Letters Patent is:

1. A paper holder of the class described comprising a supporting member having a main body; angularly turned ends projected outwardly from said main body and extending in parallel spaced relation, each of said ends having notches formed in its outer edge adjacent the upper end thereof and each of said ends having an opening formed therein; a U shaped retaining member having the ends of its legs angularly turned to engage in the said notches, the ends of said angularly turned portions of said legs projecting through said openings and pivotally mounting said retaining member on said supporting member.

2. A paper holder of the class described comprising a supporting member having a main body; angularly turned ends projected outwardly from said main body and extending in parallel spaced relation, each of said ends having notches formed in its outer edge adjacent the upper end thereof and each of said ends having an opening formed therein; a U shaped retaining member having the ends of its legs angularly turned to engage in the

said notches, the ends of said angularly turned portions of said legs projecting through said openings and pivotally mounting said retaining member on said supporting member; a pair of springs each connected at 5 one end to said supporting member and at the opposite end to said retaining member for normally resisting disengagement of said retaining member from said notches.

3. A paper holder of the class described 10 comprising a supporting member having a main body; angularly turned ends on said main body projected outwardly in parallel spaced relation to each other, each of said ends having a notch formed in its outer edge 15 adjacent the top thereof, and provided with an opening below said notch; a U shaped retaining member the legs thereof being angularly turned to engage in said notches and engage below said notches the outer face of 20 said angularly turned ends of said supporting member, the ends of said legs being again angularly turned and projected through said openings.

4. A paper holder of the class described 25 comprising a supporting member having a main body; angularly turned ends on said main body projected outwardly in parallel spaced relation to each other, each of said ends having a notch formed in its outer edge 30 adjacent the top thereof, and provided with an opening below said notch; a U shaped retaining member the legs thereof being angularly turned to engage in said notches and 35 engage below said notches the outer face of said angularly turned ends of said supporting member, the ends of said legs being again angularly turned and projected through said openings; and resilient means for normally 40 resisting disengagement of said retaining member from said notches.

In testimony whereof I have signed the foregoing specification.

HILARY G. KNOTH.
